UNITED STATES PATENT OFFICE

EDWARD B. BEDFORD AND MARY G. PARKER, OF ONEIDA, NEW YORK, ASSIGNORS TO ONEIDA COMMUNITY, LIMITED, OF ONEIDA, NEW YORK, A CORPORATION OF NEW YORK

DESIGN FOR A GOBLET OR SIMILAR ARTICLE

Application filed July 8, 1932. Serial No. 44,283. Term of patent 7 years.

To all whom it may concern:

Be it known that we, EDWARD B. BEDFORD and MARY G. PARKER, citizens of the United States, residing at Oneida, county of Madison, State of New York, have invented a new, original, and ornamental Design for a Goblet or Similar Article, fully described and represented in the following specification and the accompanying drawing forming a part of the same, said drawing being a side elevation of a goblet showing our new design, the essential feature of which is the ornamental matter on the bowl of the goblet or similar article.

We claim:

The ornamental design for a goblet or similar article as shown and described.

In testimony whereof we have hereunto set our hands.

EDWARD B. BEDFORD.
MARY G. PARKER.
